UNITED STATES PATENT OFFICE.

GEORGE T. WOODIN, OF NEWPORT, NEW YORK.

MULTIPLE FUSE PLUG.

Application filed October 5, 1921. Serial No. 505,456.

This invention relates to multiple fuse plugs, and has for its general object to provide a plug which shall combine efficiency with convenience of operation, simplicity and compactness of construction, and economy of production. I accomplish the foregoing objects, and other and more limited objects which will appear hereinafter, in and through the construction and arrangement of parts shown in the drawing forming a part hereof, wherein Fig. 1 represents a central longitudinal sectional view through a multiple fuse plug embodying my invention, the central contact, some of the parts connected thereto, and the fuses being shown in elevation; Fig. 2 a plan view of the base, corresponding substantially to the line 2—2 of Fig. 1; Fig. 3 a bottom plan view of the cap, corresponding substantially to the line 3—3 of Fig. 1; Fig. 4 a detail in section through the central cooperating portions of the cap and base; and Fig. 5 a sectional detail corresponding to the line 5—5 of Fig. 3.

25 Describing the various parts by reference characters, 1 denotes the upper magazine member and 2 the lower socket-connection member of a base. The member 2 is provided with the usual shell plug contact 3 which is adapted to fit a threaded socket shell contact (not shown). The upper end of the sheet metal of which the contact 3 is composed is flanged inwardly above a flat seat 2^a on top of the member 2, the flange 35 constituting an annular contact surface 4.

The upper member 1 of the base is of any suitable non-conductive material such as fibre, preferably cylindrical in shape, and is provided with a plurality of bores 5 located within the peripheral portion thereof. Six such bores are shown, spaced equidistantly apart and equidistantly from the center or axis of the said member. The bottoms of these bores are located directly above the flange 4, for a purpose to be explained hereinafter.

50 The members 1 and 2 are secured together, to form a unitary base by means of the central contact 7, which is provided at its lower end with a head 8 adapted to engage the lower end of the member 2. This contact extends upwardly through central bores in both of said members, indicated at 1^b and 2^b, and is provided within a recess 9 in the upper end of the member 1 with a nut 10

which serves to draw and hold the members 1 and 2 rigidly together.

Mounted within the bores or chambers 5 are the fuses, each fuse being of the cartridge type and consisting of an ordinary fuse wire (not shown) having its ends in electrical contact with the opposite metallic ends 11^a of a casing 11. Each cartridge fuse is preferably $\frac{1}{6}$ " long and $\frac{1}{4}$ " in diameter, the body 11 being of glass and the end caps being preferably of brass. The fuses are small enough to permit them to be employed with a body 1 of standard dimensions and with their lower ends electrically seated upon the flange 4 and their upper ends below the top of such body.

Rotatably mounted upon the base and carrying a contact arm electrically connected with the contact 7 is a rotatable cap 13. The upper peripheral portion of this cap is preferably knurled, as indicated at 13^a, the cap being provided with a skirt 13^b depending from the body thereof and overlapping the upper end of the member 1. The cap is provided with a central bore 13^c having annular extensions 13^d and 13^e at the top and bottom thereof, respectively. Mounted in the annular extension 13^e is a sheet metal hub 14 carrying a contact arm. This arm, which is of resilient metal, comprises a radially extending portion 15 and a curved portion 15^a which is provided with a downwardly projecting contact finger 16. The bottom of the cap 13 is recessed for the reception of the arm members 15, 15^a as indicated at 13^f. The finger 16 is adapted to snap into the tops of the bores 5 and into contact with the upper ends of the fuses successively as the cap is rotated (through the connections to be described) in the direction of the arrow in Fig. 3. Between the bores 5, it will ride upon the top of the body 1, whereby the circuit is opened without arc-ing between adjacent fuses. The hub 14 is secured to the cap by means of a sleeve 17 having a flange 18 engaging beneath said hub and a flange 18^a on the bottom of the extension 13^d. The cap 13 is rotatably secured to the body member 1 by means of a cap 19 threaded upon the upper end of the contact 7, within the sleeve 17, and having a flange 19^a adapted to engage the flange 18^a of said sleeve.

With the parts constructed and arranged as described, the operation will be readily

understood. The base is screwed into its proper socket, with the finger 16 pressing downwardly into a bore 5 and upon the top of a cartridge 11 whereby, when a switch 5 is closed at the proper place, a circuit will be established through the shell plug contact 3, flange 4, the appropriate fuse, the finger 16, the arm 15, 15^a, the members 17 and 19, and the central contact 7. Should 10 the particular fuse wire in use burn out, it is necessary only to turn the cap 13 sixty degrees, thereby bringing the contact finger 16 into engagement with the cap of another fuse, whereupon the circuit will again be 15 established through the fuse plug. The shape of the arm 15, 15^a and finger 16 and the location of the fuses will cause the finger to "snap" into place in contact with the new fuse and thus enable the operator to determine, by the ear, as well as by the sense of 20 feeling, when the cap has been moved a sufficient distance to cause the finger to engage the top of a fuse. The top of the cap 13 will be provided with an arrow indicating 25 the direction of rotation, thereby to prevent the operator from attempting to move the arm 15 above and in engagement with the cap of a burned-out fuse. Should such attempt be made, the finger 16 and arm 15, 30 15^a act as a detent pawl through the engagement of the end of the finger with the wall of the bore in which it may be positioned. Persistence in such attempt will cause the 35 plug as a whole to be rotated and to be unscrewed from its socket, thus permitting

easy removal of the plug, if desired, as well as warning the operator as to the direction in which he is rotating the cap.

When all of the fuses have been burned out, the cap may be easily removed and new 40 cartridge fuses inserted into the chambers 5.

Having thus described my invention, what I claim is:

In a device of the character described, the combination of a base having a shell plug contact member and a body member thereabove, the latter member being provided with a plurality of bores surrounding the axis thereof, of a central contact connecting the said members, a cap rotatably mounted 45 upon the base and the second contact and having rigid therewith a resilient metallic arm having a radially extending portion and an arcuate portion substantially concentric with the axis of rotation of said cap, the second portion of the arm being provided with an angularly deflected portion defining a finger adapted to drop into the tops of the bores successively through the rotation of the cap in one direction and to serve as a detent in connection with said bores when the cap is rotated in the opposite direction, and a fuse casing in each of said bores each having its lower end in electrical 50 engagement with the first mentioned contact and having its upper end beneath the top of its bore.

In testimony whereof, I hereunto affix my signature.

GEORGE T. WOODIN.
